UNITED STATES PATENT OFFICE.

JULIUS A. BIDWELL, OF IVANPAH, CALIFORNIA.

DESIGN FOR A PIN.

SPECIFICATION forming part of Design No. 21,645, dated June 21, 1892.

Application filed April 9, 1892. Serial No. 428,536. Term of patent 7 years.

To all whom it may concern:

Be it known that I, JULIUS A. BIDWELL, a citizen of the United States, residing at Ivanpah, in the county of San Bernardino and State of California, have invented and produced a new and original Design for a Pin, of which the following is a specification, reference being had to the accompanying drawing, forming a part thereof, which represents 5 a front elevation of a pin embodying the features of my design.

The design consists in a circular figure 10, represented as overlapping a second circular figure 11, whereby the entire design may be 15 said to consist in a circular figure apparently embossed upon a semicircular figure, one appearing to support the other.

In addition to the two figures 10 and 11 as an adjunctive feature of the design, a pin-like figure 12 appears to emanate therefrom. 20

A second adjunctive feature of the design consists in the representation of what is known as the "dollar-sign" upon the full circular figure, and in the appearance upon the partially-circular figure of a portion of a similar 25 sign.

I claim—

The design for a pin, substantially as herein shown and described.

JULIUS A. BIDWELL.
